UNITED STATES PATENT OFFICE.

EDWARD P. SHELDON, GEORGE BRAND, AND FELIX MARCILE, OF BROOKLYN, NEW YORK.

LABEL-FEEDING MECHANISM.

1,177,284.

Specification of Letters Patent. Patented Mar. 28, 1916.

Application filed March 9, 1909, Serial No. 482,262. Renewed April 24, 1915. Serial No. 23,766.

To all whom it may concern:

Be it known that we, EDWARD P. SHELDON, GEORGE BRAND, and FELIX MARCILE, citizens of the United States, and residents of Brooklyn, in the county of Kings and State of New York, have invented certain new and useful Improvements in Label-Feeding Mechanisms, of which the following is a specification.

10 Our invention relates to means for supplying labels one at a time to proper position for affixing to objects to be labeled in a label affixing machine.

15 The invention is particularly useful for supplying labels affixed as bands to cigars by a banding machine of the general character described in United States patent to Edward P. Sheldon, No. 981,017, dated January 10th, 1911.

20 One part of our invention relates more particularly to the means for detaching or removing the labels one at a time from a pile of labels supported in a suitable box and carrying them to feed rolls whereby they 25 are passed successively to position where, by the operation of a plunger and other devices, they are applied or affixed to the cigar or other objects.

Another portion of our invention consists 30 of means whereby the feed of the labels may be automatically stopped in case of any interruption in the feed of the cigars or other objects to position for application of the labels.

35 In carrying out the first part of our invention, we employ a rotary suction pick-up which, by exhaust, detaches the outermost label of the pile by taking hold of the label at a point sufficiently far removed from its 40 end to cause said end to project tangentially from the pick-up so that by the motion of the pick-up bodily to a pair of feed rolls said end may be introduced between the feed rolls and detached and moved along toward 45 the label affixing portion of the machine. This part of our invention comprises also special means for rotating the pick-up after it has taken hold of the label and for causing the pick-up to dwell in position where 50 it detaches or removes the label from the pile.

Another part of our invention consists of a shield adapted to be inserted between the pile of labels and the rotary pick-up and controlled by the objects to be labeled as 55 they move toward label affixing position.

The invention consists also in the special

combinations of devices and details of construction more particularly hereinafter described and then specified in the claims.

In describing the invention it will be assumed that the articles to be labeled are cigars fed to labeling position on a collapsible support or platform as described in the prior application above referred to. Inasmuch as the invention has to do particularly with the portion of the apparatus for feeding the bands or labels and is applicable to other machines for affixing the labels, the drawings and specification have been confined, for the sake of brevity, to such portion of the machine, and the other appliances for feeding the cigars or other objects and for applying the band or label have been omitted.

Figure 1 is a plan of an apparatus embodying our invention. Fig. 2 is a side elevation of the same. Figs. 3 and 4 show the label moistening device with a detaching finger in two different positions. Fig. 5 illustrates the manner in which the shield for holding the labels against removal from their pile may be controlled by the feed of the cigars or other objects toward banding or label affixing position. Fig. 6 is an end elevation of the device shown in Fig. 5.

1 indicates the framework of the machine broken away in a vertical line between the label feed and the portion which supports the devices for feeding the cigars or other objects to label affixing or banding position upon the collapsible platform 55 or other support, as described in the prior application hereinbefore referred to.

The mechanism shown may be driven from a wheel 81 or other driving wheel connected with or forming a portion of any revolving member of the machine, as described in such prior application, said wheel 81 being indicated in dotted lines and being shown as gearing to a wheel 2.

The labels detached or removed one at a time from the pile of labels 3 are first received by a pair of feed rolls 4 and fed thereby between guide plates 5 from which they are passed on by a pair of feed rolls at the farther end of said plates 5 to a second pair of guide plates 6. They are drawn from the space between the latter pair of guide plates by means of a pair of feed rolls 7 and forced by the latter through guide plates 8 into position upon the collapsible support 55. In this position they receive

the cigar or other object to be labeled and are affixed thereto by the operation of a suitable plunger and folding and pressing devices which act when the object with the 5 label beneath it is forced down past plate 55, said devices operating in the manner described in the aforesaid application or in any other suitable way. The forward end of the label which, in the present instance 10 is supposed to have inclined sides is received between side guide plates 61 upon a support plate 60 and its forward motion is stopped by the abutment 62 which is engaged by the forward end of the label. Proper motion 15 is given to the various feed rolls through a train of gears, geared up to wheel 2, as clearly shown, and which need not be described in detail as its construction and operation will be obvious to those skilled in 20 the art.

The label holding box holding the pile of labels 3 is properly mounted on a plate or frame 9 secured to the main frame of the machine. When the labels are detached one 25 at a time from the pile, as herein described, from beneath, said pile is supported at one end by a plate 10 whose free end is preferably somewhat inclined downwardly to facilitate the movement of the label when it is 30 detached or removed and slips down past the free edge of the plate 10. At its opposite end the pile is supported by a plate 11 normally projecting a slight distance beneath the edge of the pile so as to allow the 35 label to bend freely and clear said support when it is drawn downward by the action of the pick-up device which detaches or removes the labels one at a time from the pile and which acts upon them as will be presently 40 described. The plate 11 also acts as a guard plate to prevent detachment of labels when the feed of cigars or other objects is interrupted from any cause, and for this purpose is adapted to be reciprocated endwise beneath the pile of labels and to interpose itself between the pile and the exhaust tube 12 of the suction pick-up which is 45 mounted and operated as will be presently described.

50 13 is a lever connected to the shield 11 and normally maintained in position shown by the action of the cigars or other objects as they move in a train or series to label affixing position.

55 A suitable weight 14 carried upon an arm projecting from the rock shaft 15 which supports lever 13 acts to move the plate or shield 11 inward to shield the labels against the action of the suction device 12 when 60 freed from the restraining influence of the cigars or other objects exerted on the lever 13 through a connecting rod 16, as shown in Fig. 5, tied to an arm extending from a rock shaft 17, carrying fingers or 65 arms 18 which lie in the path of the cigars

or other objects 19 as they are fed by the band feed 20 toward position upon the platform 55. As shown in said Fig. 5 when there is no interruption in the train of cigars or other objects the fingers 18 will be 70 held down in position indicated in dotted lines and the shield 11 will be held against the influence of the weight 14 in the position shown in Fig. 2. In case there should be a cessation in the regular feed of the cigars 19, the arms or fingers 18 will be permitted to rise to the position shown in full lines, and the weight 14 will thereby be permitted to move the shield 11 endwise beneath the pile of bands 3 and prevent further detachment of the labels by the action of the pick-up device.

The pick-up device for removing or detaching the labels one at a time from the pile operates by exhaust of air and suction applied through the medium of a tube 12, the mouth of which may be located in the periphery of a suitable wheel 21 mounted to rotate in suitable bearings on a reciprocating support 22 carried by rock shaft 23. 85 The shaft of wheel 21 is a hollow shaft affording a passage which communicates with the exhaust tube 12 on the one hand and on the other communicates with a flexible tube 24 applied to the hollow end of the shaft, 90 as shown in the plan view, and connected with a suitable exhaust pump.

The support 22 is reciprocated toward and away from the initial pair of feed rolls 4 by any proper device but preferably by 100 means of pitman 25 connecting with a crank pin on a wheel of the label feed gear or by similar mechanical movement arranged to pass the dead center when the arm 22 and pick-up device are in position shown in 105 full lines with the mouth of the suction tube against the surface of the outermost label of the pile. By these means the suction device is caused to dwell in position for detaching the label so as to insure the 110 action thereof by suction or exhaust on said label. Movement of the pitman is communicated to the support 22 through the arm 26 fastened to rock shaft 23, and to further insure a dwell of the exhaust tube in position shown in full lines, a last motion is 115 provided by elongating the opening in the pitman where a pin projecting from the arm 26 engages in said pitman. A spring 27 connects the arm 26 and the pitman, as 120 shown, while a stop 28 limits the rearward movement of the support 22 for the pick-up device. As the crank moves in the direction of the arrow toward position shown, to cause the arm 22 to recede, the latter 125 first brings up against the stop but owing to the last motion of the crank can continue its movement and slide the pitman on the pin without producing any movement of the arm 22. After passing the center, the 130

pitman follows up the crank under the action of the spring 27 until it again engages the pin at the reverse end of the slot after which the arm 22 with the pick-up device begins its forward motion toward the position shown in dotted lines.

The label pick-up is caused to rotate from the position shown in full lines to that shown in dotted lines as it moves forward toward the feed rolls 4 by any suitable means, as for instance, by rack 29 engaged by a toothed wheel 30 on the shaft of wheel 21 or by other suitable means. Inasmuch as the suction device or tube 12 takes hold of the label at a point somewhat removed from the end it is obvious that the free, forward end of the latter will project tangentially from the wheel 21 and thereby be caused to enter between feed rolls 4 when the support 22 is moved over to the position shown in dotted lines and the wheel 21 is partially rotated with the label clinging by suction to its periphery. The rear end of the label will wrap itself partially around the wheel 21 and being detained or held between the pile of labels and the lip or plate 10 it will be finally drawn from beneath the pile and around the smooth periphery of the wheel 21 by the positive action of the feed rolls 4.

The moistening of the labels may be either a moistening with a gum or moistening by a liquid such as water applied to a previously dried and gummed surface. We have shown appliances, however, particularly designed for moistening by water, the label moistener being wetted periodically through the intervention of a wick which draws moisture from a tank 31 containing water. The moistener proper consists preferably of some absorbent substance 32 set in a periphery of one of the feed wheels 7. Said wheel carries also a detaching finger 33 set preferably in the periphery of the wheel and acting to forcibly detach the label 34 from the moistener 32, so as to prevent sticking. The spring finger 33 is compressed between the two wheels 7 with the label 34 as the latter passes between said feed wheels, but as the free end of the tongue or finger passes the point of compression it springs outwardly and detaches the moistening end of the label, in obvious manner. Fig. 4 shows the moistener as engaging the label and the spring finger as about to enter between the feed rolls. Fig. 3 shows the position assumed by the finger after it has detached the label and which position it retains until the wheel has rotated in the direction of the arrow around to position shown in Fig. 4.

The moistener 32 whether charged with water or with a gum is periodically wetted by a wetting device carried in a reciprocating support 35 pivoted at 36 on the frame of the machine and operated by a cam 37

on the shaft of the feed drive. Said cam engages, as shown in plan view, a roller 38 carried by a pivoted arm 39 attached to the support 35, said arm being sustained by a fork on the cam shaft, as better seen in 70 the side view, Fig. 2. When a liquid or other solvent for a previously gummed label is used, the wetting device embodies a wick 40 and the support 35 is simply a wick tube whose end is cut away to allow the wick to 75 engage the moistener 32. The end of the wick is kept moist by the liquid drawn up through capillary action from the tank 31 and the reciprocating movement of the tube 35 is related to the rotary movement of the 80 moistener 32 or coöordinated so that when the moistener is opposite the end of the wick tube 35 it will be permitted by the cam 37 to fall against and wet the moistener 32. The forward movement of the tube 35 is 85 for this purpose secured by the action of a suitable spring 41 bearing on the wick tube and fastened to the framework, the rearward movement to carry the wick away from engagement with the periphery of the feed 90 wheel 7 being produced by the cam acting in opposition to said spring.

In order to permit the label box or holder to accommodate labels of different lengths and having inclined edges inclined at different angles, the end plate 42 is provided with a slotted base 43 through which rises a pin carrying clamping nut 44. The two side plates 45 are similarly mounted and may obviously be adjusted to any required position with reference to the longitudinal axis of the label, so as to accommodate labels of different widths having edges differently inclined to said longitudinal axis.

The means herein described for moistening or gumming the labels and feeding them to label affixing position in condition for being affixed are not herein claimed, since they form the subject of claims in our United States Patent No. 1,050,856, dated 110 January 21st, 1913, this patent being a division of the present application.

What we claim as our invention is:

1. The combination of a label feeding mechanism, means for feeding the article to be labeled, an arm or finger in the path of the articles to be labeled and a shield or guard plate movable under the pile of labels and connected with said finger.

2. The combination of a label box or holder adapted to support a pile of labels, a plate normally engaging the outermost label of the pile near its end, a pick-up device for detaching the outermost label from the pile and drawing its end past the obstruction afforded by said plate when in normal position and means controlled by the articles to be labeled in their progress toward labeling position for moving said plate to cause the same to cover the portion of the outermost 125 label.

- label exposed to the action of the pick-up device.
3. The combination with the label holding box of a periodically acting pick-up device adapted to remove the labels one at a time from a pile supported in the box, a shield adapted to be projected under the surface of the outermost label of the pile and means controlled by the articles to be labeled in their progress toward the labeling position for operating said shield.
4. In a label feeding mechanism, the combination of a label holder carrying a pile of the labels, a plate partially engaging the pile of labels at one end and mounted on a support by which it may be moved beneath the pile and prevent the removal of the labels, means for feeding the articles to labeling position, and means operated by the articles to be labeled as they travel toward labeling position for moving said plate as and for the purpose described.
5. In a label-affixing machine, the combination substantially as described, of a label support adapted to support the label in label-affixing position, feed rolls for feeding the labels one at a time on to said support, a label holder, a rotary suction pick-up wheel provided with an exhaust tube opening in the periphery of the wheel, a reciprocating support carrying said wheel, whereby the same may be moved toward and from the feed rolls, and means for rotating the same in its forward movement to present the free end of the label to the feed rolls.
6. In a label-affixing machine, the combination of a label support adapted to support the label in label-affixing position, label feed rolls for feeding the labels successively on to said support, a label holder, a rotary suction pick-up wheel having an exhaust opening adapted to pick up a label near one end, a reciprocating support for moving said wheel bodily to and away from the label feed rolls, and means for rotating the pick-up wheel in its movement toward the feed rolls, whereby the free end of the label may be presented between said wheels.
7. In a label-affixing machine, the combination of a support adapted to sustain the labels one at a time in label-affixing position, a periodically operated feed mechanism for feeding the labels one at a time to said support, a label holder, a rotary suction pick-up mounted on a reciprocating support for detaching the labels one at a time from a pile thereof in the label holder and presenting a free end of the label to feed rolls of the feed mechanism, and mechanism for reciprocating said support arranged to pass its dead center when the pick-up is opposite the label, as and for the purpose described.
8. In a label-affixing machine, the combination of means for supporting the label in label-affixing position, feed devices feeding the labels one at a time to said support, means for supporting the labels in a pile, a rotary exhaust tube mounted on a reciprocating support and adapted to detach the outermost label of the pile by suction applied at a point removed from the end of the label, feed rolls adapted to receive the free end of the label while projected tangentially from the pick-up, and a rack and pinion for rotating the pick-up as it is moved bodily toward the feed rolls.
9. In a label-affixing machine, the combination of means for supporting the label in label-affixing position, means for feeding labels one at a time on to said support, a label box or holder for holding a pile of labels, a rotary suction pick-up for detaching the labels one at a time from the pile, feed rolls for receiving the free end of the label projected tangentially from the pick-up and devices for reciprocating the pick-up bodily toward and from the feed rolls, said devices having lost motion, as described, whereby the pick-up is caused to dwell in position for detaching the label.
10. In a label-affixing machine, the combination of means for supporting the label in label-affixing position, means for feeding the labels one at a time on to said support in gummed condition, a label holder for holding a pile of labels superposed on one another, a rotary suction pick-up, feed rolls for receiving the free end of the label, a crank and pitman for reciprocating the pick-up bodily toward and from the feed rolls and means for rotating the pick-up in its forward motion, as and for the purpose described.
11. In a label-affixing machine, the combination of means for supporting the label in label-affixing position, means for feeding the labels one at a time on to said support in gummed condition, a label-holding box having a longitudinally adjustable end plate and side plates, two on each side of the label, whose distance and inclination to the longitudinal axis of the label are adjustable, and means for removing the labels one at a time from a pile held in said box and carrying them to the said feed mechanism.
